APPARATUS FOR EXCITING LUMINOUS TUBES

Joseph Béthenod, Paris, France, assignor to Société Anonyme pour les Applications de l'Électricité et des Gaz Rares, Établissements Claude-Paz & Silva, a corporation of France

Application July 9, 1935, Serial No. 30,537
In France July 20, 1934

3 Claims. (Cl. 177—352)

Various methods of exciting luminous tubes are known, particularly with a view to showing whether or not a high-tension conductor is under tension and indicating the presence of an overland line (night beacons, etc.).

5 In order to facilitate the installation of a luminous tube thus utilised, it has been proposed to take advantage of the known properties of metallic points to increase considerably the dissipation of electricity at various points of the high-tension conductor and it has also been proposed to arrange luminous tubes on the leakage lines thus established. Such devices present serious inconveniences in practice:

10 1. The dissipating member offers to the wind a comparatively large resistance which may be detrimental to the mechanical safety of an overland line and even occasion short-circuits in the case of excessive swinging.

15 2. The points of this dissipating member are subjected by oxidation to an amount of wear which may prejudice its proper functioning after a certain length of service.

20 3. The presence of such a member greatly favours the production of damped waves which may considerably interfere with neighbouring wireless receiving stations.

25 The object of the present invention is to obviate these defects by the application of a novel method of exciting luminous tubes based on certain properties of the electrostatic field created about the high-tension conductor, to the exclusion of any disperser or similar member.

30 The invention is illustrated in the accompanying drawing, in which:

35 Figures 1 and 2 represent diagrammatically, by way of example only, embodiments thereof.

In the arrangement shown in Figure 1, a conductor 1 pertains for example to a high-tension line which it is desired to indicate by night. To this end, according to the invention, there is arranged parallel to this line an auxiliary line 2, the distance of which from the principal conductor 1 is generally a few centimetres or decimetres, and the length of which depends upon the potential of the line and the magnitude of the desired effect. At the centre 3 of this auxiliary line, which is insulated from the principal conductor by the insulators 6, there is connected one of the electrodes of a luminous tube 4. The latter may be of any shape. It may be arranged for example in the manner known per se, in helical, sinusoidal or zig-zag shape, so as to provide the greatest possible length in a small space. The other electrode being connected to the prin-

cipal conductor 1, it is found that the tube 4 lights up strongly if the various elements of the installation have been suitably chosen. It is even possible to obtain an appreciable effect when the distance between the conductors 1 and 2 is of the order of magnitude of a centimetre, and in accordance with theory, this effect increases more and more slowly with the distance present.

It should be noted that the insulating distance-piece supports 6 have only to withstand a comparatively small drop in potential, the magnitude of which correspond to the value necessary for satisfactory operation of the tube employed. The usual precautions can be taken against condensation and possible dripping of the water, though such incidents can only affect the production of the luminosity without endangering the insulation of the main line, because the respective distances of the main line and auxiliary lines from the ground are of the same order, that is, comparatively great, relative to the spacing between them so that the addition of the auxiliary line does not increase the danger of grounding the main line in the case of rain.

The positioning of the connection 3 at the centre of the auxiliary line 2 is not essential, but it will be preferable in general since it reduces to a minimum the radiation of parasitic waves produced by the discharges passing through the tube 4. From this point of view, the device forming the object of the invention affords a considerable advantage over devices comprising dispersers, which constitute aerials with a very strong radiation.

Another form of carrying out the invention is shown in Figure 2. It includes the use of two tubes 4A and 4B, each having one of their electrodes connected to the principal conductor 1, while the other electrodes are connected together by the auxiliary line 2, the length of which again corresponds to the potential of the line, the type of tubes, the effect to be obtained and other conditions. The operation of this particular arrangement with tubes connected together does not differ essentially from that of Figure 1, and it possesses similar advantages as regards the reduction of any radiation of parasitic waves.

Preferably, the auxiliary lines and tubes are arranged so that they act at the same time as vibration damping means and attenuate the mechanical vibration or swinging of the high-tension line. For this purpose, the weight and the moment of inertia of the auxiliary lines car-

rying the electrodes are selected in accordance with the desired damping effect.

Naturally, the invention covers numerous variations and in particular the auxiliary line 2 is not necessarily parallel to the principal line 4. Furthermore, the tubes may be provided with internal or external electrodes. Finally, impedances 5 intended to damp the high-frequency oscillations produced by the operation of the tubes may be inserted in the conductors connecting the electrodes and the lines 1 and 2.

I claim:

1. An apparatus for exciting gaseous luminous discharge tubes by means of a high tension conductor, comprising insulators suspended from the high tension conductor, an auxiliary line supported at its extremities between the insulators and positioned parallelly to said conductor, a luminous tube provided with spaced electrodes, means for conductively connecting one of the electrodes to the high tension conductor, and means for conductively connecting the other electrode to the auxiliary line, the distance of the auxiliary line from the high tension conductor being between a few centimeters and a few decimeters, so that the no-load potential determined in taking account only of the electrostatic induction between the high tension conductor and the auxiliary line on one hand and between the auxiliary line and the ground on the other hand to the exclusion of all discharge effects will be greater than the starting potential of the tube employed and the length of the auxiliary line being such that at the aforesaid distance of the same from the high tension conductor the potential at the terminals of the tube after starting will be substantially equal to the normal potential of operation of the tube.
2. An apparatus for exciting gaseous luminous discharge tubes by means of a high tension conductor, comprising insulators suspended from the high tension conductor, an auxiliary line supported at its extremities between the insulators and positioned parallelly to said conductor, a luminous tube provided with spaced electrodes arranged parallel to said conductor, means for conductively connecting one of the electrodes to the high tension conductor, means for conductive-

ly connecting the other electrode to a center point of the auxiliary line, the distance of the auxiliary line from the high tension conductor being between a few centimeters and a few decimeters, so that the no-load potential determined by taking account only of the electrostatic induction between the high tension conductor and the auxiliary line on one hand and between the auxiliary line and the ground on the other hand to the exclusion of all discharge effects will be greater than the starting potential of the tube employed and the length of the auxiliary line being such that at the aforesaid distance of the same from the high tension line the potential at the terminals of the tube after starting would be substantially equal to the normal operating potential of the tube.

3. An apparatus for exciting gaseous luminous discharge tubes by means of a high tension conductor, comprising insulators suspended from the high tension conductor, an auxiliary line supported by its extremities between the insulators parallel to said conductor, a luminous tube provided with spaced electrodes, means for conductively connecting one of the electrodes to the high tension conductor, means for conductively connecting the other electrode to the auxiliary line, impedances interposed in at least one of the connecting means, the value of said impedances being adapted to damp the high frequency oscillations produced by the operation of the tube, the distance of the auxiliary line from the high tension conductor being between a few centimeters and a few decimeters, so that no-load potential determined by taking account only of the electrostatic induction between the high tension conductor and the auxiliary line on one hand and between the auxiliary line and the ground on the other hand to the exclusion of all discharge effects will be greater than the starting potential of the tube employed and the length of the auxiliary line being such that at the aforesaid distance of the same from the high tension line the potential at the terminals of the tube after starting will be substantially equal to the normal operating potential of the tube.

JOSEPH BETHENOD.
